UNITED STATES PATENT OFFICE.

MARKO MAYERLE AND MICHAEL MAYERLE, OF KANSAS CITY, KANSAS.

DESIGN FOR A WEAPON.

49,489.

Specification for Design.

Patented Aug. 8, 1916.

Application filed June 3, 1916. Serial No. 101,622. Term of patent 7 years.

To all whom it may concern:

Be it known that we, MARKO MAYERLE and MICHAEL MAYERLE, subjects of the Emperor of Austria-Hungary, residing at Kansas City, in the county of Wyandotte and State of Kansas, have invented a new, original, and ornamental Design for a Weapon, of which the following is a specification, reference being had to the accompanying drawing, forming part thereof.

The figure is a view in side elevation of a weapon, showing our new design.

We claim:—

The ornamental design for a weapon, as shown.

MARKO MAYERLE.
MICHAEL MAYERLE.

Witnesses:

JOE SLAK,
MILLIE SLAK.
